UNITED STATES PATENT OFFICE.

CARROLL E. DODSON, OF KANSAS CITY, MISSOURI.

SOUNDING WHEELED TOY.

1,302,776.

Specification of Letters Patent.

Patented May 6, 1919.

Application filed September 18, 1917. Serial No. 182,218.

To all whom it may concern:

Be it known that I, CARROLL E. DODSON, a citizen of the United States, residing at Kansas City, in the county of Jackson, State of Missouri, have invented certain new and useful Improvements in Sounding Wheeled Toys, of which the following is a full and exact specification.

The present invention relates to improvements in toy structures, and aims to provide an improved toy device of the animated or mechanical type. Accordingly, one of the objects in view is to devise a novel construction comprising a movably mounted figure made in the likeness of an animal and provided with means whereby the progressive forward movement of the device will actuate said figure to simulate the characteristic movements of said animal.

It is a further object to devise a toy construction of this character wherein novel means is provided for producing a sound simulating the characteristic cry of the animal which is represented.

It is also sought to provide a simple, strong and durable, as well as neat and extremely inexpensive construction embodying said features of improvement. Minor objects will appear in the course of the detailed description.

With these general objects in view the invention will now be described with reference to the accompanying drawing illustrating one form of construction which has been devised for embodying the improvements, after which those features and combinations deemed to be novel will be set forth in the appended claims.

In the drawing—

Figure 1 is a side elevation (partly broken away) showing a toy constructed in accordance with the present invention;

Fig. 2 is an inverted plan view of the same; and

Fig. 3 is a side elevation, partly in section, showing parts of the toy in different operative position, one side of the supporting structure being omitted for clearness of illustration.

Referring to the drawing in detail, this illustrates a wheel-supported structure comprising a frame member 4 having secured to its under face a pair of longitudinal side pieces 6. These side pieces 6 are provided with front and rear recesses 8, within which are fitted for rotative movement the front

and rear axles 10 and 12, respectively, carrying the several wheels 14, the latter being preferably constructed of wood and fitted on flattened terminals at the ends of said axles 60 (see Fig. 2). The axles 10 and 12 are retained within the recesses 8 by means of staples 16.

The frame member 4 is provided with a longitudinal slot 18 (see Fig. 2) for the purpose of movably mounting a figure piece 20 which is cut out in the likeness of an animal, in the present instance a duck; and for pivotally mounting said figure the same is equipped with a pin 22 adjacent the forward 65 end of said slot 18, the opposite ends of said pin being carried in staples 24. The figure piece 20 is provided with a movable jaw 26 and with a tongue 28 lying between said movable jaw 26 and the fixed jaw 30 of said 70 figure. This tongue 28 is made of any suitable material, preferably somewhat flexible, in order that the rear end of said tongue may be utilized for forming the hinge element 32 of the movable jaw 26, as shown in Figs. 75 1 and 3. The movable jaw 26 is held normally in closed position (that is, during the time when the body portion of the figure 20 is in lowered position, as illustrated in Fig. 1) by means of a rod 34 which projects up 80 through a passage 36 provided in said figure piece 20 and into engagement with said jaw 26 near its rear end. The rod 34 is bent laterally at its lower end, as shown at 38 (Fig. 2), which laterally bent portion is retained 85 by means of a staple 40. The passage 36, as formed for the rod 34, allows some play of said rod, and a pin 42 is provided in said passage for definitely limiting the rearward movement of the rod. Whenever the body 90 portion of the figure 20 is raised, it will be obvious that its head portion will be moved forward a certain extent, with the result that the hinged portion of the movable jaw 26 is carried slightly forward over the upper 100 end of the rod 34, thereby permitting said jaw 26 to swing down into open position as illustrated in Fig. 3.

The up and down movements of the figure 20 are effected by means of the axle 12, 105 which is formed with a crank portion 44 adapted to engage the lower edge of said figure, the latter being formed with a slightly curved concave edge portion 46 for such engagement (Fig. 3). Use is also made 110 of this crank element for actuating a sound-producing element which, in the present in-

stance, comprises a spring wire beating or striking member 48, attached at its forward end by means of staples 50 to the under face of the frame member 4, and having a curved intermediate portion 52 adapted to be held normally in engagement with said frame 4 with the rear end of said wire located in position for engagement by the crank 44. As this crank rotates in the direction indicated by the arrow in Fig. 3, it engages said rear end of the wire 48, pulls it down and then releases it, the wire then springing back sharply into engagement with the frame 4. With the arrangement and approximate proportions of the parts as illustrated by the drawing, this striking engagement of the wire 48 is adapted to produce a sound approximately simulating the "quack" or cry which is characteristic of the duck represented by the figure 20. The arrangement is also such that this sound is produced during the time when said movable jaw 26 is in open position.

It will thus be apparent that a neat, simple and durable construction has been devised for carrying out the desired objects of the invention. The operation of the crank first effects upward movement of the figure 20, thereby also causing the jaw 26 to open by moving the same forward over the end of the rod 34. Thereupon the crank engages and operates the wire striking member 48 to produce the "quacking" sound characteristic of the duck, after which the crank allows the figure to come down into entirely lowered position. This carries the jaw 26 back over the end of the wire 34, thereby causing said jaw to be swung back into closed position. The construction and mode of operation are such that the device is not likely to get out of order, and the same is well adapted for manufacture at small expense.

While the foregoing illustrates what is now deemed to constitute the preferred form of construction, the right is reserved to such formal changes and modifications as may fairly fall within the scope of the appended claims.

50. What I claim is:

1. A mechanical toy comprising a figure made in the likeness of an animal, a frame carrying said figure and provided with supporting wheels, one end of said figure being pivotally connected to said frame, and means actuated by the movement of said wheels into sliding engagement with the

other end of said figure and operating to raise and lower the figure to simulate the movements of the animal.

2. A mechanical toy comprising a figure made in the likeness of an animal, a frame carrying said figure and provided with supporting wheels, one end of said figure being pivotally connected to said frame, means actuated by the movement of said wheels into sliding engagement with the other end of said figure and operating to raise and lower the figure to simulate the movements of the animal, and means actuated by said first means for emitting a sound simulating the characteristic cry of the animal.

3. A mechanical toy comprising a movable figure made in the likeness of an animal and provided with a movable jaw, supporting wheels carrying said figure, means actuated by the movement of said wheels for raising and lowering said figure and simultaneously effecting opening and closing movement of said jaw, and means actuated by said first means for emitting a sound simulating the characteristic cry of the animal.

4. A mechanical toy comprising a movable figure made in the likeness of an animal and provided with a movable jaw, supporting wheels carrying said figure, and means actuated by the movement of said wheels for raising and lowering said figure, and means acting to retain said jaw in closed position when said figure is lowered and permitting said jaw to swing to open position when said figure is raised.

5. A mechanical toy comprising a figure made in the likeness of an animal and provided with a movable jaw, and a flexible member formed to represent the tongue of the animal and having one end portion of said member acting as a hinge for said jaw.

6. A mechanical toy comprising a movable figure made in the likeness of an animal and provided with a movable jaw, supporting wheels carrying said figure, means actuated by the movement of said wheels for raising and lowering said figure and simultaneously effecting opening and closing movement of said jaw, and a striking member actuated by the movement of said wheels to deliver a blow producing a sound simulating the characteristic cry of said animal.

In witness whereof I affix my signature.

CARROLL E. DODSON.
